United States Patent Office.

JOHN M. CAIN, OF LAFAYETTE, WISCONSIN, ASSIGNOR TO GEORGE CAIN, OF SAME PLACE.

Letters Patent No. 87,756, dated March 16, 1869.

IMPROVED HAT-HOLDER FOR PEWS AND SEATS.

The Schedule referred to in these Letters Patent and making part of the same.

To all whom it may concern:

Be it known that I, JOHN M. CAIN, of Lafayette, in the county of Walworth, and State of Wisconsin, have invented an Improved Hat-Holder, for Churches and Public Halls; and I do hereby declare that the following is a full and exact description thereof, reference being had to the accompanying drawings, making part of this specification—

Figure 1 being a view of the device, as attached to the under side of a bench, or seat, for use.

Figure 2, a view of the same detached, and drawn full size.

Like letters designate corresponding parts in both figures.

Let D represent an ordinary seat, or bench.

My invention consists of a swinging wire or bent-rod bracket, A, and a holder, B, attached to the swinging end of the bracket, constructed and operating substantially as herein specified.

The bracket A consists of a simple rod, or wire, bent to a form approximating to that of the letter U, as represented, one end being somewhat longer than the other.

An eye, a, is formed on the end of its longer arm, to receive a pivot, c, on which it turns, and which may be a simple wood-screw.

The eye-portion is best made by bending the wire itself into form, and at right angles to the main stem, so that the bracket may hang about vertically under the seat.

The shorter, or swinging arm C, of the bracket, is provided with a hoop, or ring-holder, B, which may be made of wire, with a central cross-rod, b, for attaching it to the arm C of the bracket. This attachment may be by means of a socket, as shown, or in any equivalent manner.

The holder may turn on the bracket, and be removable, if desired.

The entire instrument, thus constructed, is pivoted to the under side of the bench, or seat, just under the rear edge, as shown, so that it can be swung backward, to receive a hat or cap, as indicated in red lines in fig. 1, and then swung forward again under the seat, out of the way.

It is exceedingly simple and cheap, and does not obstruct the seat in the least.

The circular form of the holder B keeps the hat or cap in proper position, so that it can rest close up under the seat.

I am aware that wire hat-holders and brackets have been used, and I do not claim them; nor do I claim the application of movable hat-holders to the bottoms of church and hall-seats, such having been before used, but of different construction and operation from mine; and I am not aware that a pivoted wire bracket and holder, like that above described, has ever been combined with the seat of a church or public hall. Therefore,

What I claim as my invention, and desire to secure by Letters Patent, is—

The U-shaped wire bracket A, provided with a wire holder, B, and with a pivot-eye, a, in combination with and pivoted to the bottom, D, of a church or hall-seat, as herein specified.

The above specification signed by me, this 13th day of July, 1868.

J. M. CAIN.
